UNITED STATES PATENT OFFICE

SAMUEL JASGUR, OF BROOKLYN, NEW YORK

WINDOW SHADE ADJUSTING DEVICE

Application filed April 1, 1929. Serial No. 351,671.

My invention relates to adjustable window shades and refers particularly to devices having two vertical channel shaped members and adapted for the raising and lowering of window shades or curtains.

The rollers carrying window shades, or curtains, are usually attached to opposite sides of a window frame and hence are not capable of being raised or lowered.

10 This fixed position of the curtain roller is objectionable as the unrolled curtain prevents the free access of air when the upper window sash is lowered, and as it is frequently desirable to obtain free access of air through the upper open portion of the window, while using the curtain as a screen only for the unopen portion, it is evident that a device which will accomplish this result is of great value and convenience.

20 The device of my invention produces this desirable result in an effective manner as will be evident upon a consideration of my specification and its accompanying drawings.

25 In the accompanying drawings illustrating one form of the device of my invention, similar parts are designated by similar numerals.

Figure 1 is a front view of one form of my device attached to a window frame.

30 Figure 2 is an enlarged section through the line 2—2 of Figure 1.

Figure 3 is an enlarged section through the line 3—3 of Figure 2.

35 Figure 4 is an enlarged section through the line 4—4 of Figure 1.

Figure 5 is an enlarged section through the line 5—5 of Figure 1.

Figure 6 is a perspective view of one curtain carrier.

40 Figure 7 is a perspective view of the other curtain carrier.

Figure 8 is an enlarged section through the line 8—8 of Figure 5.

45 Figure 9 is an enlarged section through the line 9—9 of Figure 2.

Figure 10 is a perspective view of a modified form of curtain carrier.

50 In the accompanying drawings illustrating one form of the device of my invention in operative position, I show a window frame

having the bottom 10, the sides 11 and 12, the top 13 and carrying the upper sash 14 and the lower sash 15.

Attached to the inner face of the frame side 11 is a channel-shaped member 16 having a longitudinal slot 17 therein formed by a cut-out and inwardly bent portion 18. The said channel-shaped member 16 is attached to the frame side 11 by means of a screw passing through a hole in its foot 19 and is attached to the frame top 13 by means of a screw passing through its angularly positioned head 20.

55 A bushing 21 is inserted through an opening in the lower portion of the member 16, within which is a revolute shaft 22 carrying a toothed wheel 23 within the member 16 and a knurled wheel 24.

Vertically slidable within the slot 25 of the member 16 is a rod 26, having a knurled 70 knob 27 exterior of the device, and a downwardly projecting pointed member 28 capable of placement between the teeth of the sprockets of the wheel 23.

Attached to the inner face of the frame side 12 is a channel-shaped member 29 having a vertical slot, similar to the channel-shaped member 16 and its slot. Within the lower portion of the member 29 is a sprocket wheel 30 revolute upon the stud shaft 31 80 and spaced from the face of the member 29 by the spacer 32. A lock nut 33 retains these elements in position.

75 The two upper portions of the channel-shaped members 16 and 29 are connected by two revolute rods 34 and 34 slidable within the sleeve 35 and maintained in desired position therein by the set-screws 36, 36. The ends of the rods 34, 34 within the channel-shaped members 16 and 29 carry the 85 sprocket-wheels 37, 38.

A chain belt 39 connects the drive sprocket 23 and the sprocket 37 and a chain belt 40 connects the two sprockets 30 and 38.

90 Within the channel-shaped member 16 is a curtain support 41, to which the chain 39 is attached, the upper portion 42 of the curtain support being bent and extending outwardly through the slot 17, the member 41 100 has three angular openings 43, 44 and 45.

Within the channel shaped member 29 is a curtain support 46 to which the chain 40 is attached, the upper portion 47 of the support being bent and extending outwardly through the longitudinal slot of member 29. The member 46 has the two round openings 48 and 49 and the angular opening 50.

The end carriers of a spring-operated curtain 51 are placed in the openings 48 and 49 and the end carriers of a second spring-operated curtain 52 are placed in the openings 45 and 49.

The operation of the device is as follows:

For purposes of supporting drapery, or curtains, I employ two angular members 53, 53, each one of which is capable of insertion in one of the angular openings 44 and 50. The exposed end portion 54 of each of the members 53, 53 carries an upwardly extended double prong member 55, each pair of opposite prongs being capable of supporting a drapery support 56.

The operation of my device is as follows, assuming that the device is in its utmost upward position and it is desired to lower the upper sash 14 and to lower the device accordingly:

The knob 27 is raised thus allowing the revolution of the sprocket 23. The knob 24 is then revolved, which revolves the sprocket 23, moving the chain 39, revolving the sprocket 37, the rods 34 and 35 and the sprocket 38, moving the chain 40 and revolving the sprocket 30. It will thus be seen that the two chains 39 and 40 move in unison, carrying the curtain carriers 41 and 46 with their attached curtains. The revolution of the knob 24, therefore, moves the curtains up or down to the desired position and the lowering of the knob 27 retains them in the desired position. If it is desired that draperies be moved at the same time, the members 53, 53 are employed as above described. The extended members 42 and 47 prevent the accidental spring unrolling of the shades, as the wooden cross-piece of the extremity of the shade can not pass between the rolled shade and the members 42 and 47.

The modified form of curtain carrier shown in Figure 10 comprises a channel-shaped member 60 having an acute-angled member 61 which is vertically slidable over the inwardly extended member 18 of the channel guide 16, the member 18 thus acting as a guide for the vertical movement of the curtain carrier.

It will thus be seen that my device presents an easily operative means for raising or lowering a shade, or curtain, roller, to a desired position within a window frame.

I do not limit myself to the particular size, shape, number, arrangement or material of parts as shown and described as these are given simply as a means for clearly describing the device of my invention.

What I claim is:—

1. In a device of the character described, in combination, two vertical channel-shaped members the base of each having a longitudinal slot therein for attachment to inner opposing sides of a window-frame, the base of each channel-shaped member being spaced from said window-frame and the two arms of said channel-shaped member being directed inwardly toward said window-frame, a revolute sprocket in each channel-shaped member, means exterior of said channel-shaped member adapted to revolve one of said sprockets, a revolute shaft connecting the two said channel-shaped members, a sprocket attached to each end of said shaft and within one of said run-ways, chain belts within said run-ways and connecting the shaft sprockets with the other two said sprockets, a curtain-carrier fixedly attached to opposite points of the two said belts and means for maintaining said carrier at any desired vertical position. 70

2. In a device of the character described, in combination, two vertical channel-shaped members the base of each having a longitudinal slot therein for attachment to inner opposing sides of a window-frame, the base of each channel-shaped member being spaced from said window-frame and the two arms of said channel-shaped member being directed inwardly toward said window-frame, a revolute sprocket in each channel-shaped member, means exterior of said channel-shaped member adapted to revolve one of said sprockets, a revolute shaft connecting the two said channel-shaped members, a sprocket attached to each end of said shaft and within one of said run-ways, chain belts within said run-ways and connecting the shaft sprockets with the other two said sprockets, a curtain-carrier fixedly attached to opposite points of the two said belts and means for maintaining said carrier at any desired vertical position. 80

3. In a device of the character described, in combination, two vertical channel-shaped members the base of each having a longitudinal slot therein for attachment to inner opposing sides of a window frame, the base of each channel-shaped member being spaced from said window-frame and the two arms of said channel-shaped member being directed inwardly toward said window-frame, a revolute sprocket in each channel-shaped member, means exterior of said channel-shaped member adapted to revolve one of said sprockets, a revolute shaft connecting the two said channel-shaped members, a sprocket attached to each end of said shaft and within one of said run-ways, chain belts within said run-ways and connecting the shaft sprockets with the other two said sprockets, a curtain-carrier fixedly attached to opposite points of the two said belts, means for maintaining said carrier at any desired vertical position, an angular member carried by each said curtain carrier, and a drapery supporting rod carried by said angular members. 90

3. In a device of the character described, in combination, two vertical channel-shaped members the base of each having a longitudinal slot therein for attachment to inner opposing sides of a window frame, the base of each channel-shaped member being spaced from said window-frame and the two arms of said channel-shaped member being directed inwardly toward said window-frame, a revolute sprocket in each channel-shaped member, means exterior of said channel-shaped member adapted to revolve one of said sprockets, a revolute shaft connecting the two said channel-shaped members, a sprocket attached to each end of said shaft and within one of said run-ways, chain belts within said run-ways and connecting the shaft sprockets with the other two said sprockets, a curtain-carrier fixedly attached to opposite points of the two said belts, means for maintaining said carrier at any desired vertical position, an angular member carried by each said curtain carrier, and a drapery supporting rod carried by said angular members. 100

3. In a device of the character described, in combination, two vertical channel-shaped members the base of each having a longitudinal slot therein for attachment to inner opposing sides of a window frame, the base of each channel-shaped member being spaced from said window-frame and the two arms of said channel-shaped member being directed inwardly toward said window-frame, a revolute sprocket in each channel-shaped member, means exterior of said channel-shaped member adapted to revolve one of said sprockets, a revolute shaft connecting the two said channel-shaped members, a sprocket attached to each end of said shaft and within one of said run-ways, chain belts within said run-ways and connecting the shaft sprockets with the other two said sprockets, a curtain-carrier fixedly attached to opposite points of the two said belts, means for maintaining said carrier at any desired vertical position, an angular member carried by each said curtain carrier, and a drapery supporting rod carried by said angular members. 110

3. In a device of the character described, in combination, two vertical channel-shaped members the base of each having a longitudinal slot therein for attachment to inner opposing sides of a window frame, the base of each channel-shaped member being spaced from said window-frame and the two arms of said channel-shaped member being directed inwardly toward said window-frame, a revolute sprocket in each channel-shaped member, means exterior of said channel-shaped member adapted to revolve one of said sprockets, a revolute shaft connecting the two said channel-shaped members, a sprocket attached to each end of said shaft and within one of said run-ways, chain belts within said run-ways and connecting the shaft sprockets with the other two said sprockets, a curtain-carrier fixedly attached to opposite points of the two said belts, means for maintaining said carrier at any desired vertical position, an angular member carried by each said curtain carrier, and a drapery supporting rod carried by said angular members. 120

3. In a device of the character described, in combination, two vertical channel-shaped members the base of each having a longitudinal slot therein for attachment to inner opposing sides of a window frame, the base of each channel-shaped member being spaced from said window-frame and the two arms of said channel-shaped member being directed inwardly toward said window-frame, a revolute sprocket in each channel-shaped member, means exterior of said channel-shaped member adapted to revolve one of said sprockets, a revolute shaft connecting the two said channel-shaped members, a sprocket attached to each end of said shaft and within one of said run-ways, chain belts within said run-ways and connecting the shaft sprockets with the other two said sprockets, a curtain-carrier fixedly attached to opposite points of the two said belts, means for maintaining said carrier at any desired vertical position, an angular member carried by each said curtain carrier, and a drapery supporting rod carried by said angular members. 130

- shaft sprockets with the other two said sprockets, a curtain-carrier fixedly attached to opposite points of the two said belts, means for maintaining said carrier at any desired vertical position, an angular member carried by each said curtain-carrier, a drapery supporting rod carried by said angular members, a spring actuated curtain roller carried by the curtain carrier and means preventing the accidental revolution of said curtain roller.
4. In a shade carrying device having two vertical channel-shaped members, two removable vertical channel-shaped members capable of attachment to opposing side faces of a window frame, the base of each said channel-shaped member having a longitudinal slot therein, the base of each said channel-shaped member being spaced from said window frame and the two arms of each said channel-shaped member being directed inwardly toward said window frame; a revoluble sprocket within the upper portion of each channel-shaped member; a revoluble sprocket within the lower portion of each channel-shaped member, the planes of said sprockets being parallel to the plane of the respective side face of said window-frame; a sprocket chain connecting the two sprockets within each channel-shaped member; means exterior of said channel-shaped members adapted to revolve one said sprocket; an extensible revoluble shaft connecting two opposed sprockets in the two said channel-shaped members; a longitudinally movable curtain carrier extending through the two said longitudinal slots and fixedly attached to a said sprocket chain in each channel-shaped member and means carried by said curtain carrier to support a curtain.
5. In a shade carrying device having two vertical channel shaped members, two removable vertical channel-shaped members capable of attachment to opposing side faces of a window frame, the base of each said channel-shaped member having a longitudinal slot therein, the base of each said channel-shaped member being spaced from said window frame and the two arms of each said channel-shaped member being directed inwardly toward said window frame; a revoluble sprocket within the upper portion of each channel-shaped member; a revoluble sprocket within the lower portion of each channel-shaped member, the planes of said sprockets being parallel to the plane of the respective side face of said window-frame; a sprocket chain connecting the two sprockets within each channel-shaped member; means exterior of said channel-shaped members adapted to revolve one said sprocket; an extensible revoluble shaft connecting two opposed sprockets in the two said channel-shaped members; a longitudinally movable curtain carrier extending through the two said longitudinal slots and fixedly attached to a said sprocket chain in each channel-shaped member and means carried by said curtain carrier to support a curtain.
6. In a shade carrying device having two vertical channel shaped members, two removable vertical channel-shaped members capable of attachment to opposing side faces of a window frame, the base of each said channel-shaped member having a longitudinal slot therein, the base of each said channel-shaped member being spaced from said window frame and the two arms of each said channel-shaped member having a longitudinal slot therein, the base of each said channel-shaped member being spaced from said window frame and the two arms of each said channel-shaped member being directed inwardly toward said window frame; a revoluble sprocket within the upper portion of each channel-shaped member; a revoluble sprocket within the lower portion of each channel-shaped member, the planes of said sprockets being parallel to the plane of the respective side face of said window-frame; a sprocket chain connecting the two sprockets within each channel-shaped member; means exterior of said channel-shaped members adapted to revolve one said sprocket; an extensible revoluble shaft connecting two opposed sprockets in the two said channel-shaped members; a longitudinally movable curtain carrier extending through the two said longitudinal slots and fixedly attached to a said sprocket chain in each channel-shaped member and means carried by said curtain carrier to support a curtain.

by said curtain carrier to support a curtain and means preventing the accidental spring-unrolling of a curtain carried by said curtain carrier.

5 Signed at New York city in the county of New York and State of New York this 28th day of March, 1929.

SAMUEL JASGUR.
